UNITED STATES PATENT OFFICE.

MELVILLE W. MIX, OF MISHAWAKA, INDIANA.

DESIGN FOR A PHONOGRAPH-CABINET.

58,156.

Specification for Design.

Patented June 14, 1921.

Application filed February 12, 1920. Serial No. 358,240½. Term of patent 14 years.

To all whom it may concern:

Be it known that I, MELVILLE W. MIX, a citizen of the United States, residing at Mishawaka, in the county of St. Joseph and State of Indiana, have invented a new, original, and ornamental Design for a Phonograph-Cabinet, of which the following is a specification, reference being made to the accompanying drawing, forming part thereof.

The figure shows, in a perspective view, the phonograph cabinet in which the corners round off into the body without a break in conjunction with the ornamental base, and molded top.

I claim:

The ornamental design for a phonograph cabinet, as shown.
